AUTOMATIC SNUFFER FOR ASH TRAYS

Larry Lowy, Rockaway Park, N. Y.

Application January 4, 1941, Serial No. 373,116

3 Claims. (Cl. 131—235)

This invention relates to new and useful improvements in ash trays, and has more particular reference to an automatic snuffer for lighted cigarettes balanced on edge portions of tray.

Still further the invention proposes to characterize the automatic snuffer by an ash tray body having an elevated concave cigarette support member across which a cigarette may be placed, and said ash tray body also having a snuffing groove element below said cigarette support member into which the stub portion of said cigarette will fall when it burns to a point to unbalance the cigarette.

Still further the invention proposes several novel constructions for the snuffing groove element to effectively encase and constrict the major portion of the lighted end of the cigarette stub to snuff it out.

The invention further contemplates to so arrange the automatic snuffer that it may be embodied in ash trays of various shapes, sizes and designs.

Another object of the invention resides in so constructing the automatic snuffer that it may be integral with the ash tray body, or arranged in an auxiliary portion of the body thereof.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of an ash tray provided with several automatic snuffer elements constructed in accordance with this invention.

Fig. 2 is a plan view of Fig. 1.

Fig. 3 is a fragmentary vertical sectional view taken on the line 3—3 of Fig. 2.

Fig. 4 is a fragmentary vertical sectional view similar to Fig. 3 but showing an ash tray with a snuffer constructed according to a modified form of the invention.

Fig. 5 is a plan view of another ash tray embodying the same invention.

Fig. 6 is a vertical sectional view taken on the line 6—6 of Fig. 5.

Fig. 7 is a fragmentary plan view of another ash tray constructed in accordance with another form of this invention.

Fig. 8 is a fragmentary enlarged vertical sectional view taken on the line 8—8 of Fig. 7.

Fig. 9 is a fragmentary plan view of another

ash tray embodying still another form of this invention.

Fig. 10 is a fragmentary vertical sectional view taken on the line 10—10 of Fig. 9.

Fig. 11 is an end elevational view of one of the snuffer groove elements shown in Fig. 10.

Fig. 12 is an end elevational view of another one of the snuffer groove elements shown in Fig. 10.

10 The automatic snuffer for ash trays, in accordance with this invention, is used in combination with an ash tray body 15 having an elevated concaved cigarette support member 16 across which a cigarette, indicated by the dot and dash lines 17, may be balanced. The ash tray body 15 is also provided with a snuffing groove element 18 located below the cigarette support member 16 into which the stub portion of the cigarette 17 may fall when it burns to a point so as to unbalance it from its position of balance on the cigarette support member 16.

15 The ash tray body 15 may be of any size, shape, material and construction. As illustrated, the body 15 is provided with a large recessed top central portion 20 into which the ashes of cigarettes and cigars may be dropped. This central portion 20 is surrounded with a wall portion 21. The wall portion 21 has a narrow flat top edge portion 21^a which is too narrow to support a cigarette in balance. This wall 21 also has beveled top portions 21^b which are arranged so as not to facilitate the support of a cigarette on the wall 21. Consequently it is necessary for a person to place a cigarette on the concave cigarette support member, or members 16, when it is desired to place the cigarette on the ash tray.

20 The body 15 is provided with more than one of the cigarette support members 16 as clearly illustrated in Fig. 1. The grooves 18 are formed in auxiliary portions 15^a of the body 15 which project from the sides thereof at points below the cigarette support members 16. The body 15, and its auxiliary portions 15^a are shown integral. However, this is merely a matter of choice since the body may be constructed of separate sections, connected, or placed together.

25 In Fig. 4 a modified form of the invention has been disclosed in which the auxiliary section 15^{aa} is of a separate material from the body section 15, and is releasably connected therewith with holding pegs 22.

30 Each snuffing groove element 18 has a shallow outer end portion 18^a and a deep inner end portion 18^b. These end portions are so arranged that the stub portion of a cigarette which burns

to a point that it is unbalanced, will first fall down so that its outer end engages the shallow outer end 18^a of the snuffing groove element 18. Thereafter, upon continued burning, the lighted end will fall into the deep constricting portion 18^b of the snuffing groove element. This will cut off the air from the bottom and sides of the cigarette stub so that the ember will soon be extinguished.

In Figs. 5 and 6 a modified form of the invention has been disclosed which distinguishes from the prior form essentially in the shape of the ash tray body. In accordance with this form of the invention the automatic snuffer for ash trays is used in combination with an ash tray body 25 having one or more elevated concave cigarette support members 26 across which a cigarette may be placed. The body 25 is provided with one or more snuffing groove elements 27 for each cigarette support member 26 into which the stub portion of a cigarette will fall when it burns to a point to unbalance the cigarette.

The ash tray body 25 has an annular wall portion 28 with a comparatively narrow top edge 28^a and beveled sides 28^b. At one, or more points, this wall portion 28 is formed with the cigarette support member, or members 26. The cigarette body 25 has auxiliary extensions 25^a from the sides thereof, at points below the cigarette support members 26. The snuffing groove elements 27 comprise recesses formed in the body 25 and the auxiliary portions 25^a of the body. Each snuffing groove element 27 has a shallow outer end 27^a and a deep constricting inner end 27^b.

In other respects this form of the invention is similar to the previous forms and like parts are identified by like reference numerals.

In Figs. 7 and 8 another form of the invention has been disclosed which is very similar to the form shown in Figs. 5 and 6, distinguishing merely in the fact that each snuffing groove element 27 has its side walls 27^x constructed in a resilient way. More specifically, each side wall 27^x has a slot 30 extended longitudinally thereof along the sides and communicating with an internal cavity 31. The cavity 31 divides off a comparatively thin compass of material forming the side walls 27^x. Consequently, these walls are soft and resilient.

When a cigarette stub falls into the groove element 27, the side walls 27^x will be forced outwards and then resiliently engage the sides of the lighted cigarette, helping to extinguish same.

In Figs. 9 and 10 another form of the invention is disclosed which distinguishes from the prior forms in the arrangement and construction of the snuffing groove elements. In accordance with this form of the invention it is applied to an ash tray body 33 having an elevated concave cigarette support member, or members 34 across which a cigarette may be balanced. The body 33 is provided with one or more snuffing groove elements 35, 36, etc., located below said cigarette support member, or members 34 into which the stub portion of said cigarette will fall when it burns to a point to unbalance the cigarette.

The snuffing groove element 35 is formed from sheet material, or other material and is of hollow semi-cylindrical form. It is provided with a rubber suction cup 37 upon its bottom, by which it is releasably attached to the body 33. The snuffing groove element 36 is of similar construction, except that it is of V-shape in transverse cross section. This element 36 is also provided with a suction cup 37 mounted on its bottom side by which it is releasably mounted on the material of the ash tray body 33.

In other respects this form of the invention is similar to the previous forms and like parts are identified by like reference numerals.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. An automatic snuffer for ash trays, comprising an ash tray body having an elevated concaved cigarette support member across which a cigarette may be placed, and said ash tray body having a snuffing groove element below said cigarette support member into which the stub portion of said cigarette will fall when it burns to a point to unbalance said cigarette, said snuffing groove element having a shallow outer end and a constricting enlarged inner end.

2. An automatic snuffer for ash trays, comprising an ash tray body having an elevated concaved cigarette support member across which a cigarette may be placed, and said ash tray body having a snuffing groove element below said cigarette support member into which the stub portion of said cigarette will fall when it burns to a point to unbalance said cigarette, said snuffing groove element having a shallow outer end and a constricting enlarged inner end, and the side walls of said snuffing groove element being resiliently arranged to resiliently engage the sides of said stub portion.

3. An automatic snuffer for ash trays, comprising an ash tray body having an elevated concaved cigarette support member across which a cigarette may be placed, and said ash tray body having a snuffing groove element below said cigarette support member into which the stub portion of said cigarette will fall when it burns to a point to unbalance said cigarette, said snuffing groove element having a shallow outer end and a constricting enlarged inner end, and the side walls of said snuffing groove element being resiliently arranged to resiliently engage the sides of said stub portion, each of said side walls having a longitudinally extending groove near its bottom communicating with a cavity to the rear of said side wall.

LARRY LOWY.
